METHOD OF PASTEURIZING LIQUIDS

Filed July 14, 1925

UNITED STATES PATENT OFFICE.

FREDERIK LASSEN, OF COPENHAGEN, DENMARK, ASSIGNOR TO AKTIESELSKABET
DE FORENEDE BRYGGERIER, OF COPENHAGEN, DENMARK.

METHOD OF PASTEURIZING LIQUIDS.

Application filed July 14, 1925, Serial No. 43,656, and in Great Britain June 23, 1925.

This invention relates to method of pasteurizing liquids. More specifically it relates to a method and apparatus for pasteurizing liquids which contain gases which escape on heating and whose presence in the liquids is desirable. Beer is an important member of this class of liquids.

As is well known, beer is pasteurized after it is bottled. It is extremely important that this pasteurization should be complete, especially if the beer is to be shipped. Owing to the considerable expansion of the liquid on heating, the bottles cannot be filled entirely. The small air space thus left in the bottle prevents the complete pasteurization of the contents. It is extremely difficult to ensure the pasteurization of the gases in the air space. The air space causes the liquid in the bottle to toss during transport, especially during sea transport. This tossing is detrimental to the liquids, especially if they contain absorbed liquids.

This invention eliminates these drawbacks. According to this invention, the liquid to be pasteurized is heated in expandable containers. The containers are completely, or as completely as practicable, filled with the liquid. The containers and the contained liquid are then heated to the pasteurizing temperature. When the pasteurization is completed, the containers are cooled. The heating of the liquids causes them to expand, thus causing an expansion of the container. On cooling the liquids contract. Usually the containers are so constructed that the partial vacuum resulting from the contraction of the liquids, is insufficient to cause the restoration of the original volume of the container. Under such circumstances a small gas space will remain at the top of the container.

It is desirable to remove this air space when the liquid is to be shipped in the container in which it is pasteurized. This removal of the air space is desirable because it prevents the tossing of the liquid during shipment. It also causes the reabsorption of the gases in the air space. Another important consideration is that containers full of liquid are better able to withstand mechanical forces than containers only partially filled.

In the process of this invention, the containers after cooling are exposed to an ex-

ternal pressure sufficient to restore them to 55 their original volume. The container is then completely filled with liquid and the liquid contains the same gases as before pasteurization. According to this invention the pasteurization process is carried out in 60 containers having an expandable portion. This is obtained by constructing the container so that a wall portion shall be made of a thinner or softer metal than the rest of the container. This wall portion expands when the liquid is heated. It may be restored to its original thus restoring the container to its original volume.

This invention may be further understood by reference to the accompanying drawings 70 wherein,

Figure 1 is a side elevation of a pasteurizing plant with part of the tank broken away, showing the containers in place and having their smallest volume.

Figure 2 shows an expandable container having its greatest volume.

Figure 3 is an end elevation of Figure 1.

Figure 4 is a plan top view of Figure 1.

In the modification illustrated in the drawings, the expandable container consists of a metal bottle *a*, the bottom of which is made of softer or thinner material than the remainder of the bottle. When the pressure in the interior of the container corresponds to that at the ordinary temperature, the bottom *b*¹ of the container is concave. Owing to the relative weakness of the bottom, it may bulge (*b*² Fig. 2) when the interior pressure increases during pasteurization.

For example the bottle may be made of aluminium, the bottle proper being made of hard aluminium and the bottom of softer aluminium.

If such bottles be made to hold 25 liters, they can compete economically with common beer bottles. They may be produced so cheaply that they need not be returned to the breweries or other pasteurizing plant. As stated before, a more stable product is obtainable than when containers having a small air space is employed.

Many different devices for pasteurizing the liquids in expandable containers and many different devices for exerting an exterior pressure on the containers after pasteurization, may be employed. The pres-

sure may for example be exerted hydraulically. I prefer however the embodiment illustrated. This plant consists of any type of pasteurizing vat *h*, provided with means 5 for circulating hot water to obtain the required pasteurizing temperature and means for circulating cold water for cooling purposes. The vat is also provided with communicating compartments in which the containers are placed. A guide rod *d* runs down the center of the vat. The containers are placed in rows on either side of this rod. Each of the containers rests on a standard *c*. The containers are closed by a cap *g*, provided with the necessary packing. A lever *e* is slidably mounted on the rod *d* and capable of being swung to either side of the tank. On this lever is a block *f* containing a recess 10 which fits over the cap *g*.
When the containers are heated, the expansion of the liquid forces the bottom from concave to the convex position. After the containers are cooled, the lever is brought over the cap. The force exerted by this lever 15 combined with the reaction of the standard
20

forces the bottom inwards thus restoring the original volume of the containers.

The above description of my invention is not to be taken as limiting but rather as illustrative of my invention which,

I claim is:

1. A method for pasteurizing liquids containing dissolved gases without loss of gas during pasteurization which comprises heating a volume of the liquid in a confined space whereby dissolved gases are partially liberated but kept in the confined space, cooling the liquid and by external, positively applied pressure, re-dissolving the gases therein.

2. A method for pasteurizing liquids containing dissolved gases, said pasteurization being carried out out of contact with air, which comprises heating the liquid in a confined space, said liquid substantially filling said space, cooling the liquid and by external, positively applied pressure, redisolving in the liquid any gases liberated during the heating.

In testimony whereof I affix my signature.
FREDERIK LASSEN.
